UNITED STATES PATENT OFFICE

2,615,469

MOTOR-DRIVEN BLOWOFF VALVE

Wilfred C. Schofield, Chicago, Ill., assignor, by
mesne assignments, to Koppers Company, Inc.,
a corporation of Delaware

Application May 4, 1946, Serial No. 667,451

1 Claim. (Cl. 137—703)

1

The present invention relates to improvements in blow-off valves.

More particularly, the present invention relates to improvements in blow-off valves such as used in connection with blast furnace stoves.

A blast furnace stove is operated alternately to heat air being delivered to a blast furnace, the heat for the purpose being stored in checker-brick or the like within the stove. During other periods the checkerbrick within the stove is heated by burning blast furnace gas within the stove.

At times when the stove is on blast the pressure in the stove may range from one to three atmospheres above atmospheric pressure. When the stove is on gas, that is, while the stove is being heated, the pressure within the stove is commonly approximately atmospheric.

When the stove is being changed from air to gas, that is, when it has given up its heat and is to be heated, the valve connecting the stove to the source of cold blast is closed and the hot blast valve connecting the stove to the blast furnace is closed. As noted above, the pressure within the stove is substantially above atmospheric and it is necessary to discharge the air from the stove under considerable pressure. It is a function of the blow-off valve to relieve the stove by discharging this air to the atmosphere.

An object of the present invention is to provide an improved blow-off valve having the advantage that it is unnecessary that the operating means therefor be stopped exactly at a predetermined position.

A further object is to provide an improved blow-off valve involving a mechanical movement having the characteristics of a toggle.

A further object is to provide an improved blow-off valve in which it is unnecessary to provide a brake.

A further object is to provide an improved blow-off valve having the advantage that, at the start of opening movement of the valve disc, the driving means has a large mechanical advantage whereby it may force the disc open against a substantial pressure.

A further object is to provide a blow-off valve having the advantage that a motor for operating said valve may have a flying start, enabling the motor to gain momentum before it is required to start the opening movement of the valve disc.

A further object is to provide an improved blow-off valve which is simple and sturdy in construction and not likely to get out of order.

A further object is to provide an improved

blow-off valve well adapted to meet the needs of commercial service.

Further objects will appear as the description proceeds.

Referring to the drawings:

Figure 1 is a view in side elevation, parts being broken away, illustrating one embodiment of the present invention; and

Figure 2 is a view in end elevation of the structure illustrated in Figure 1.

The numeral 10 indicates the main body portion of a blow-off valve. Said body portion has connected thereto a pipe 11 which may lead to a hot blast stove. A pipe 12 leading to said body portion may be connected to the atmosphere.

The body portion 10 includes the conduit portion 13 which is illustrated as being in the form of an elbow, one end being connected to the vertically disposed pipe 12 and the other end being connected to the horizontally disposed pipe 11. Said conduit portion adjacent to pipe 11 is flanged as indicated by numeral 14 and is provided with the replaceable valve seat 15 having a circular aperture bounded at its outer extremity by a conical portion adapted to receive a corresponding conical portion of the valve disc 16. Said valve disc 16 is loosely and resiliently carried by the valve stem 17, which valve stem is horizontally disposed and is carried by the supporting portion 18 rigid with the body portion 10.

The casting which comprises the body portion 10 of the valve is open at the side thereof opposite to the flange 14, this opening being covered by the housing 19. The outer extremity of the housing 19 is provided with the aperture 20 closed by means of the removable cover plate 21.

The valve stem 17 slides within bearings, one of which is indicated by numeral 22. The end of the stem 17 opposite to disc 16 is provided with the rack portion 23 adapted to have a sliding movement along the floor of the housing 19. The upper side of the rack portion 23 is provided with teeth 25—25 adapted to be engaged by the teeth of a pinion 26 which will be referred to more in detail presently.

The valve stem 17 adjacent to its left extremity is reduced in diameter as indicated by numeral 27, forming a shoulder 28 having abutting relationship with the boss 29 forming part of the valve disc 16. Said boss 29 is centrally apertured and is adapted to have a reciprocating and a slight rocking movement with respect to the reduced portion 27 of the valve stem 17. The valve stem 17 at its left extremity, as the parts are viewed in Figure 1, is provided with the nut 30 and

disposed upon the reduced portion 27 between the nut 30 and the boss 29 is the spring 31, which spring has the function of resiliently urging the boss 29 against the shoulder 28 of the valve stem 17. Numeral 32 indicates a cup-shaped member secured to the outer surface of the valve disc 16 and providing a cover to prevent leakage past the valve stem.

Mounted at the top of the valve body 10 is a mounting member 33 which supports a driving motor 34, an operating shaft 35, and a train of gearing (not illustrated) between said motor and said shaft 35. The numeral 36 indicates a hand wheel which may be connected to said train of gearing at an intermediate point therein whereby movement of the valve disc 16 may be accomplished manually, the number of turns of the hand wheel being restricted to a practical value.

The connection between the shaft 35 and pinion 26 may be described as follows. The pinion 26 is carried by shaft 37 which has keyed thereto the crank 38. The shaft 35 has geared thereto the crank 39. The swinging extremities of the cranks 38 and 39 are connected together by means of the rod 40. Preferably the rod 40 will be of a length to permit a complete rotation of crank 39. Rotation of the crank 38 will be limited to an angle of approximately ninety degrees, this angularity being limited by the permissible movement of rack member 23. In rotating the crank 38 through approximately ninety degrees the crank 39 will turn through a maximum of one hundred and eighty degrees. With this arrangement it is possible to open and close the valve disc 16 with either direction of rotation of the shaft 35, and overtravel on the part of the shaft 35 will do no harm. If the crank 39 travels past dead center it simply reverses the valve action. By reason of the loose and resilient connection between the valve stem 17 and the valve disc 16 a rocking movement of said valve disc is permitted after it has reached its seat. In view of the permissible axial movement between the stem 17 and the valve disc 16, it is unnecessary to have accurate stopping of the valve drive mechanism. The numeral 41 indicates as a whole a limit switch for controlling the motor 34, which limit switch is connected to the shaft 35 through a pair of bevel gears 42-42.

The mode of operation of the above described embodiment of the present invention is substantially as follows:

Ordinarily it will probably be preferred to operate the shaft 35 in a counter-clockwise direction (as the parts are viewed in Figure 1) for closing valve disc 16. Figure 1 illustrates in full lines a desired position of the two cranks 38 and 39 when the valve disc 16 just touches its valve seat, no relative movement having yet taken place between valve stem 17 and valve disc 16. At this point the limit switch 41 will de-energize the motor 34 and the inertia of the mechanism will cause the crank 39 to move further, thereby compressing the valve spring 31 and increasing the braking load on the motor 34 until the mechanism stops. It is unnecessary to have accurate stopping of the valve drive mechanism. Furthermore, the compression of spring 31 increases the load on the drive mechanism as soon as the valve disc seats. This causes the mechanism to stop without the necessity of a mechanical brake. The tension of spring 31 will be adjusted to increase the load sufficiently to stop motor 34 before the mechanism passes dead center and starts to open the valve after a complete closure.

In opening the valve disc 16, the crank 39 will be moved in a clockwise direction through approximately one hundred and ten degrees to the position indicated in dotted lines in Figure 1. At this point the limit switch 41 will cut off the power supply to the motor 34 and the mechanism will drift to rest, retarded only by the friction in the drive equipment. The crank 39 will actually come to rest approximately at its dead center position and the valve disc 16 will be at its maximum open position. However, it is unnecessary for the crank 39 to stop at dead center as the valve will open adequately with the crank 39 at any position up to approximately forty degrees on either side of dead center position.

The cranks 38 and 39 and the rod 40 comprise a power transmitting linkage having the characteristics of a toggle and the driving crank 39 is near its dead center positions at the two extremities of travel of the rack member 23. This makes it unnecessary that the motor be stopped exactly and it permits omission of a brake, the approximate toggle action of the crank 39 serving in connection with the worm gear drive to hold the valve in its open position.

The above described embodiment of the present invention has the advantage that at the start of the opening movement of the valve disc 16 the motor 34 has a large mechanical advantage so that it is able to force the disc open against a substantial pressure. The fact that spring 31 has been previously compressed enables the motor to get a flying start before the motor is required to start the opening movement of the valve disc. As indicated above, the mechanism may be operated independently of motor 34, the hand wheel 36 being provided for manual operation. Inasmuch as said hand wheel 36 is connected to an intermediate point in the train of gearing between the motor 34 and the shaft 35 the number of turns of the hand wheel required for operation of shaft 35 may be restricted to a practical value.

Though a preferred embodiment of the present invention has been described in detail many modifications will occur to those skilled in the art. It is intended to cover all such modifications that fall within the scope of the appended claim.

What is claimed is:

In a blow-off valve for the release of gases under superatmospheric pressure from the interior of a hot blast furnace stove to the atmosphere after a blast period, in combination, a housing having a valve seat, a valve disk for said seat, a reciprocable stem loosely carrying said disk, said stem being provided with a spring for resiliently urging said disk longitudinally with respect to said stem, a rack and pinion drive for longitudinally moving said stem, said valve disk being positioned on the opposite side of said valve seat from said rack and pinion drive, said spring being positioned to urge said valve disk toward said rack and pinion and toward said valve seat by the longitudinal movement of said stem during the closing of the valve, to be compressed by the longitudinal movement of said stem during the final stage of valve closing and to be released from compression during the first stage of movement of said stem to open said valve, a crank for activating said rack and pinion drive, an operating crank, a rigid rod pivotally attached to and connecting the swinging extremities of said cranks, and a motor for operating said operating crank, said cranks, rod, valve disk, valve stem and motor being adapted

to cooperate with said spring so that said spring will give said valve disk and valve stem a flying start by the release of compression thereof upon initiation of the movement of the valve stem to open the valve at the same time that said cranks and rod are in a position to exert the greatest mechanical advantage and hence the greatest force for opening said valve and will act as a brake to brake said motor and as a cushion to prevent valve damage by the compression thereof during the final stage of valve closing when the cranks and rod are in a position to exert the greatest mechanical advantage for asserting the greatest force for closing said valve and for transmitting the braking action of said spring to said motor.

WILFRED C. SCHOFIELD.
